Primary Examiner—Ruth McInroy*Attorney, Agent, or Firm*—Sterne, Kessler, Goldstein & Fox
P.L.L.C.[57] **CLAIM**

The ornamental design for a wrist support, as shown and described.

DESCRIPTION

FIG. 1 is a perspective view of a wrist support showing our new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a rear view thereof.

The broken line showing of a wrist and hand in FIG. 1 is environmental only and forms no part of the claimed design.
